UNITED STATES PATENT OFFICE.

CHARLES D. LANNING, OF BOSTON, MASSACHUSETTS.

WEFT-THREAD-CONTROLLED ELECTRICALLY-ACTUATED AUXILIARY MECHANISM FOR LOOMS.

1,301,280.

Specification of Letters Patent. Patented Apr. 22, 1919.

Application filed January 13, 1906, Serial No. 295,837. Renewed August 2, 1917. Serial No. 184,176.

To all whom it may concern:

Be it known that I, CHARLES D. LANNING, a citizen of the United States of America, residing at Boston, in the county of Suffolk and Commonwealth of Massachusetts, have invented certain Improvements in Weft-Thread-Controlled Electrically-Actuated Auxiliary Mechanism for Looms, of which the following is a specification.

10 The invention relates to electrically actuated mechanism in looms, which is auxiliary to that which operates the so-called going parts thereof, the electrical action of which auxiliary mechanism is prevented by the presence of the weft-thread, and is permitted by the absence thereof.

In this arrangement where sets of contact terminals are provided upon both sides of the loom and independently connected together by a normally open section of conductor, and all the terminals of one polarity are upon one side of the loom and are connected with one of the main conductors, and all the terminals of the other polarity are upon the other side of the loom and are connected with the other main conductor, the circuit cannot be closed unless contact is made with one of each set of terminals upon each side of the loom simultaneously, 25 for the reason that it must be closed through the normally open section of the conductor which connects the additional set of contacts.

In the accompanying drawings, Figure 1 is a plan view of a portion of the breast-beam, on which the feelers or weft-forks are supported, as shown, one at each end and a portion of the lathe upon which the terminals of the electric circuit are secured, 35 portions of the woven fabric are also shown; Fig. 2 is a side elevation of a loom-frame with a portion of the mechanism involved in the operation of the improvements hereinafter described; Fig. 3 is a plan view 40 of the electric terminals, here shown as secured behind the perpendicular rods which form the grid for the weft-fork in the customary construction of looms, and a weft-thread in front of the grid; Fig. 4 is a side 45 elevation of the parts shown in Fig. 3 with a feeler in position as it approaches the terminals; Fig. 5 is a diagrammatic illustration of the electric circuit including two sets of terminals of opposite polarity, and 50 the coöperating additional set of contacts

independently connected, as they may be arranged at each side of a loom, with all those of one polarity connected to one conductor of the circuit, and those of the other polarity on the other side of the loom connected with the other conductor, and the electro-magnet with the connected devices to release the shipper, and the switch operated by the magnet to close a short circuit through the magnet and generator.

Referring to the drawings and describing the specific embodiment of the invention therein illustrated, A designates the loom-frame, B the breast-beam, L the lathe, f the feeler, in this instance the weft-fork, 70 t t' the electric terminals, here shown as arranged in pairs of opposite polarity, M the main magnet which together with the terminals t t' are in the circuit C which also includes the electric generator G; r is 75 a lever pivoted to the frame at r' and its long arm to the armature or core of the magnet M at m'. The short arm of the lever r is arranged in a position to push the shipper-lever S from its retaining notch, when 80 the magnet pulls upon the long end of the lever r. d is one of the gears by which the take-up mechanism is operated, and e a ratchet gear in the same train which is prevented from retrograde movement while engaged by the retaining pawl p. h are perpendicular rods which form a grid in front of the ends of the terminals t t', and when employed assist the weft-thread g' in guarding the terminals from contact by the circuit closer, such as the feeler f, best seen in Figs. 3 and 4.

Referring to Fig. 5, s' is a switch operated by the magnet M, and the operation of which switches in a short circuit c' through 95 the generator and magnet, by the contact of the switch arm with the terminals c², c³.

The operation of the improvements is as follows:—Referring first to the diagram Fig. 5, in such figure, all the terminals of one polarity are upon one side of the loom and are connected with one of the main conductors, and all the terminals of the other polarity are upon the other side of the loom and are connected with the other main conductor, a normally open section c⁵ being interposed between said sets of terminals. It is apparent that the circuit cannot be closed unless contact is made with one of each set of terminals upon each side 100 105 110

of the loom simultaneously. If the weft-thread is not properly placed in front of the terminals t t' upon one side or the other of the loom and between them and a feeler 5 f , when the loom is in operation, a feeler f will be brought into contact with the terminals upon both sides and close the circuit C through the open section c^5 , magnet M , spring contact w and shipper-lever S , this 10 will energize the magnet and cause it to operate the switch-lever s' , one end of which will be drawn toward the core of the magnet and the other end will be thrown into contact with the terminals c^2 , c^3 , thereby 15 closing the short circuit c' , and sending an increased current from the generator through the magnet M , which will cause it to operate the lever r , thus releasing the shipper-lever S and stopping the loom.

20 In this arrangement of terminals, the circuit closer will make contact therewith, upon the side opposite to that in which the shuttle is boxed, at each pick, since no weft thread is interposed at that side of the loom, and 25 by this frequent friction of the circuit closer upon the terminals, their contact surfaces will be kept clean and free from lint and dust, and as it is necessary for a feeler to make contact with terminals upon both sides 30 of the loom simultaneously, in order to close the circuit, no alternate feeler controlling mechanism is needed. By the provision of a circuit closer, which in the present embodiment of the invention is a weft fork which 35 makes contact with terminals, the break in the circuit at said terminals is plugged by the weft fork. This insures an effective closing of the circuit.

The weft-thread controlled mechanism 40 illustrated in Fig. 5, instead of being used to operate loom stopping mechanism may be employed to actuate filling supply mechanism, the armature of the magnet M being employed to put such supply mechanism into 45 operation.

I claim:

1. In a loom, weft-thread controlled electrically actuated auxiliary mechanism, consisting of an electric circuit having therein 50 an electro-magnet and armature therefor and spaced terminal pieces of opposite polarity and circuit closing means secured to the loom structure, which spaced terminal pieces are adapted normally to be guarded by the 55 weft-thread from the circuit closing means which is adapted to enter between and to plug said terminal pieces to close the circuit, when the terminals are unguarded by the weft-thread means to reciprocate the circuit 60 closing means and the spaced terminal pieces one in relation to the other thereby to position the circuit closing means between said spaced terminal pieces and to put them into electrical contact when the weft-thread is 65 not interposed, and thereby close the circuit

and cause the magnet to operate its armature.

2. In a loom, weft-thread controlled, electrically actuated auxiliary mechanism, consisting of an electric circuit having therein 70 an electro-magnet and armature therefor and spaced terminal pieces of opposite polarity secured to the loom structure, which terminals are adapted normally to be guarded, by the weft-thread, from contact by a circuit closer, fork or feeler means secured to the loom structure and adapted to act as circuit closing means with said terminals when a weft-thread is not interposed, means to reciprocate the feeler means and terminals one 75 in relation to the other and to position the fork or feeler means between said spaced terminals to close the circuit and operate the armature of the magnet.

3. In a loom, weft-thread controlled electrically actuated auxiliary mechanism, consisting of an electric circuit having therein 80 an electro-magnet and armature therefor and terminals of opposite polarity respectively secured to the loom structure, upon 85 opposite sides of the web fabric, contact pieces upon each side of the loom, which are directly connected together and in conjunction with said terminals serve to complete the electric circuit in coöperation with a circuit closer, all of which terminals and contact pieces are adapted normally to be guarded by the weft-thread, from contact by a circuit closer; a fork or feeler supported 90 upon the loom structure upon each side of the web of fabric and each feeler serving as a circuit closer with the terminals and contact pieces upon that side, means relatively to reciprocate the feelers and opposed terminals with their contact pieces, and to put them into electrical contact to close the circuit and operate the armature of the magnet 95 when a weft-thread is not interposed upon either side of the loom.

4. In a loom, weft-thread controlled, electrically actuated stop-mechanism, consisting of an electric circuit with an electro-magnet and terminals of opposite polarity in the circuit, tilting fork or feeler means adapted 100 to act as a circuit closer with said terminals, but normally held from such action by the weft-thread, means relatively to reciprocate the feeler means and terminals to put them into electrical contact when the weft-thread is not interposed, thereby closing said circuit 105 and causing the magnet to operate the stop-mechanism.

5. In a loom, weft-thread controlled, electrically actuated stop-mechanism, consisting of an electric circuit having an electro-magnet and terminals of opposite polarity therein, means in proximity to the terminals to assist the weft-threads to guard the terminals from contact by a circuit closer, feeler 115 means upon the loom structure which acts 120

125

130

- as a circuit closing means with said terminals, but normally held from such action by the weft-thread, means to bring the feeler means and terminals into electrical contact 5 when the weft-thread is not in guarding position, and mechanism which is operated by said magnet to stop the loom when the circuit is closed.
6. In a loom provided with weft-fork 10 means and opposed grid upon the structure, weft-thread controlled electrically actuated stop mechanism, comprising shipper mechanism, an electric circuit, spaced contact terminals of opposite polarity therein, located 15 back of one or more of the openings in the grid, means to plug the terminals by the weft-fork means to close the circuit when the weft-thread is not in position to guard the grid openings, and an electro-magnet in 20 the circuit operatively connected with said shipper mechanism, whereby the latter is operated when the circuit is closed.
7. In a loom, provided with a grid upon 25 the lathe and weft-fork means on the loom structure, electrical weft-stop mechanism consisting of electrical spaced contact terminals of opposite polarity to be plugged by the weft-fork means, back of the openings in the grid, a magnet and armature therefor, 30 means connected with the armature which act directly to release the shipper when the armature is operated, and an electric circuit which includes the magnet and contact terminal in series.
- 35 8. In a loom, having shipper mechanism, weft-fork means, and grid upon the lathe, electrical weft-stop mechanism consisting of electrical spring contact terminals of opposite polarity adapted to be engaged by the 40 weft-fork means and located back of the grid and coincident with the openings therein, a magnet and armature therefor, means connected with the armature which act to release the shipper when the armature is operated, and an electric circuit which includes the magnet and the contact terminals, 45 which circuit is closed at said terminals when the weft-fork means passes through the grid.
- 50 9. In a loom, having weft-fork means, and opposed grid upon the lathe, electrical weft-stop mechanism consisting of one or more pairs of parallel electrical spring terminals behind the grid, the two terminals of 55 each pair being of opposite polarity and the space intervening between them being coincident with an opening in the grid; a magnet and armature therefor; means connected with the armature which act to release 60 the shipper when the armature is operated, an electric circuit which includes the magnet and each pair of terminals, which circuit is closed when the weft-fork means passes between the terminals, and a short 65 circuit through the magnet and generator which is closed by the operation of that magnet due to the current in the circuit established by the contact of the weft-fork means with the terminals.
10. In a loom, weft thread controlled 70 electrically actuated mechanism consisting of an electric circuit having therein an electro-magnet, an armature therefor, terminal pieces of opposite polarity and circuit closing means, said terminal pieces being 75 guarded normally by the weft thread from contact by the circuit closing means, said circuit closing means acting to plug said terminal pieces to close the circuit when the terminals are unguarded by the weft thread, means relatively to move the circuit closer and the terminal pieces, thereby to plug the latter when the weft thread is not interposed, to close the circuit and to cause the magnet to operate its armature. 80
11. In a loom, weft-thread controlled, 85 electrically actuated, auxiliary mechanism consisting of an electric circuit having therein an electro-magnet and armature therefor and terminal pieces of opposite polarity secured to the loom structure, which terminals are adapted normally to be guarded by the weft-thread, from contact by a circuit closing means, fork or feeler means secured to the loom structure and adapted to act as circuit closing means with said terminals when a weft-thread is not interposed, means to reciprocate the feeler means and terminals one in relation to the other and to put them 90 into electrical contact to close the circuit and operate the armature of the magnet. 95
12. In a loom in combination, weft thread controlled, electrically actuated stop mechanism comprising an electric circuit with an electro-magnet and terminals of opposite 100 polarity in the circuit, tilting fork or feeler means adapted to act as circuit closing means with said terminals but normally held from such action by the weft thread, and means relatively to reciprocate said 105 feeler means and terminals, to plug the terminals and put them in electrical contact when the weft thread is not interposed, thereby closing said circuit and causing the magnet to operate the stop mechanism. 110
13. In a loom, thread controlled electrically actuated mechanism consisting of an electric circuit, terminal pieces of opposite polarity and circuit closing means, adapted 115 to penetrate between said terminals so as to contactingly plug them said terminal pieces being guarded normally by the thread from contact by circuit closing means, said circuit closing means acting by said penetrating action to plug said terminal pieces to close the circuit when the terminals are unguarded, and means relatively to move the circuit closer and the terminal pieces, thereby to plug the latter to close the circuit. 120
14. Textile mechanism comprising in com- 125

- bination electrically actuated mechanism consisting of an electric circuit having an electro-magnet and an armature, terminal pieces of opposite polarity and circuit closing means, adapted to penetrate between said terminals so as to contactingly plug them said terminal pieces being normally guarded from contact by the circuit closing means, said circuit closing means acting by 10 said penetration to plug said terminal pieces to close the circuit when the terminals are unguarded, and means relatively to move the circuit closer and the terminal pieces, thereby to plug the latter to close the circuit.
- 15 15. In a loom, weft thread controlled electrically actuated auxiliary mechanism, consisting of an electric circuit having therein an electro-magnet and armature therefor and terminals of opposite polarity secured 20 to the loom structure upon both sides of the web of fabric, with all the terminals of one

polarity electrically connected with one of the main circuit conductors, and all the terminals of the other polarity connected with the other main circuit conductor, all 25 the terminals of both polarities being adapted normally, to be guarded by the weft thread, from contact by a circuit closer; a fork or feeler on the loom structure upon each side of the web of fabric, and each 30 feeler serving to act as a circuit closer with terminals upon that side; mechanism relatively to reciprocate the feelers and opposed terminals to put them into electrical contact to close the circuit when a weft 35 thread is not interposed upon either side of the loom.

CHARLES D. LANNING.
